Primary Examiner — Vy Koenig*Assistant Examiner* — Kimberly Barnes(74) *Attorney, Agent, or Firm* — Palmer C. DeMeo;
Palmer Patent Consultants, LLC(57) **CLAIM**

I claim the ornamental design for a roof pipe flashing, as shown and described.

DESCRIPTION

FIG. 1 is a perspective view of the roof pipe flashing showing my new design;

FIG. 2 is a top plan view thereof;

FIG. 3 is a bottom plan view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a perspective view of the roof pipe flashing for a second embodiment of my new design;

FIG. 9 is a top plan view thereof;

FIG. 10 is bottom plan view thereof;

FIG. 11 is a front elevational view thereof;

FIG. 12 is a rear elevational view thereof;

FIG. 13 is a left side elevational view thereof; and,

FIG. 14 is a right side elevational view thereof.
